UNITED STATES PATENT OFFICE.

ROBERT M. HARDISON, OF BOSTON, MASSACHUSETTS, ASSIGNOR, BY MESNE ASSIGNMENTS, TO KALMAN STEEL COMPANY, OF CHICAGO, ILLINOIS, A CORPORATION OF DELAWARE.

FLAT-SLAB CONSTRUCTION.

Application filed May 24, 1921. Serial No. 472,111.

To all whom it may concern:

Be it known that I, ROBERT M. HARDISON, a citizen of the United States, and a resident of Boston, in the county of Suffolk and State of Massachusetts, have invented an Improvement in Flat-Slab Constructions, of which the following description, in connection with the accompanying drawings, is a specification, like characters on the drawings representing like parts.

This invention relates to reinforced concrete construction and more particularly to flat-slab constructions, that is to say, to that type of building construction employing a reinforced concrete slab in which the load upon the floor is carried directly to the slab-supporting member, which may be a column or any other suitable support.

The invention and its aims and objects will be readily understood from the following description, taken in connection with the accompanying drawings of several illustrative embodiments of the invention, the invention in its true scope being more particularly set forth in the appended claims.

In the drawings:

Fig. 1 is a top plan view of a construction embodying an illustrative form of the invention, certain parts being shown in section;

Fig. 2 is a lateral, sectional elevation of the construction shown in Fig. 1, on line 2—2 of said figure;

Fig. 3 is a vertical sectional elevation on line 3—3 of Fig. 1;

Fig. 4 is a top plan view of a construction embodying another illustrative form of the invention, certain parts being shown in section;

Fig. 5 is a lateral sectional elevation of the construction shown in Fig. 4.

Figs. 6 and 8 are vertical, sectional elevations, illustrating the application of the invention to wall columns;

Figs. 7 and 9 are plan views of the construction shown in Figs. 6 and 8, respectively;

Fig. 10 is a vertical sectional elevation, illustrating the application of the invention

to wall beams, when the wall columns are not in alignment with interior columns; and

Fig. 11 is a top plan view of the construction shown in Fig. 10.

In carrying out my invention, I provide a metal head contained in the slab and preferably anchored therein, and a vertical structural member contained, and preferably anchored in the column or other support, the said head being secured or anchored to the said vertical member. The head may be of any suitable shape and structure, solid or of more or less composite structure and of annular, polygonal or any other suitable contour. The structural member may consist of a single piece such as an H-iron or iron of any other suitable shape, or it may be composite consisting of, for example, connected rods or other irons. Any suitable types of structural connections may be used, the connections necessarily varying with the different types of columns.

Referring to Figs. 1 to 3, wherein the support consists of a column, the vertical structural member anchored in the concrete column 2 consisting of an H-iron 4, while the head anchored in the slab 6 is of composite structure, consisting of a spider-like construction and comprises two iron plates 8 and 10, herein disc shaped, each having a central oblong opening through which extends the H-iron 4 forming the vertical member. The discs are secured to the web 12 and flanges 14, 14 of the H-iron, forming the vertical member, by four angle irons 16, 16, 16, 16, bolted at their opposite ends to

said discs 8 and 10 and to the web and flanges of said vertical H-iron member as shown at 18. The two plates or discs 8 and 10 are spaced apart sufficiently to receive between them the inner end portions of radially extending members, herein comprised of smaller H-iron members 20. Herein twelve such radial members are provided, but any suitable number may be used. The inner end portions of said radially disposed H-irons 20 are secured by their flanges to said discs by bolts as shown at 22. The vertical member 4 will preferably extend above

and below the floor, but this is not essential; in the case of an upper floor or a roof, for example, it will extend only below the floor or roof. The vertical members connected 5 to the heads of successive floors may be interconnected..

Referring to Figs. 4 and 5, therein the vertical structural member anchored in the concrete column 2 comprises a series of steel 10 or iron rods 24 extending longitudinally of the column 2 within the latter. In the illustrative embodiment of the invention shown in these two figures, these rods are divided into two series, each series disposed in a 15 circle, the lower screw-threaded ends 30 of the upper series secured in the top plate 26 of the head by nuts 28—28 screwed onto said screw-threaded ends upon opposite sides of said plate. The lower series are 20 secured by their upper screw-threaded ends in the lower plate 30 of said head by nuts 32, disposed similarly to the nuts 28. The free ends of said rods may be bent or turned 25 inwardly as shown in Fig. 5 to give additional purchase.

The head is similar in construction to the head shown in Figs. 1 to 3 and comprises the two plates or discs 26 and 30 referred to parallel to each other and spaced sufficiently to receive the inner ends of radial steel or iron members 34. These members, as herein shown, consist of H-irons and their inner ends are secured to the plates or discs 26 and 30 by bolts as shown at 36, said bolts 30 extending through said plates and through the flanges of said radial members. There are also provided four other radially disposed members 38, which extend practically to the center of the plates 26, 30, the inner 35 ends of two of said members 38 which are in alignment with each other being secured to the inner ends of the two other members 38, which are also in alignment with each other, by angle irons 40 and bolts 42 by which the webs of these four radial members 38 are 40 rigidly secured together. The flanges of one pair of these radial members 38 are cut away for a certain distance from their inner ends so as to enable the webs thereof to be 45 brought into position to be secured, as above described, to the webs of the other two members 38 by the angle irons. Preferably these 50 four radial members 38 will also be secured to both plates or discs by bolts 44.

55 In the construction shown in Figs. 4 and 5 the structural member also extends above and below the floor. This however is not essential and either the upper or the lower series of rods 24 may be omitted under certain 60 conditions, as the case may be; for example in the case of the uppermost floor, or in the case of a roof, the upper series of rods 24 may be omitted. The vertical rods 24 of the members of different floors may be interconnected.

My invention is applicable to columns of all kinds. In Figs. 6 to 9 I have shown two illustrative applications thereof to wall columns. In Figs. 6 and 7 the structural member anchored in the wall column 50 consists 70 of an I-iron 52 to which the head, anchored in the slab 54, is secured. Herein the head comprises a plurality of smaller I-beams, bolted by their flanges to plates 55—55 between which their inner ends extend, these 75 plates being in turn secured to the web of the I-iron 52 by angle irons 56—56 and bolts 58. The usual beam is shown at 59.

In Figs. 8 and 9 the head comprises a plurality of I-irons 58 bolted, as at 60, to 80 plates 62, 62 between which they extend, the structural member encased in the column consisting of iron rods 64 extending upwardly and downwardly from said plates to which their inner screw-threaded ends are 85 secured by nuts 66 upon opposite sides of said plates.

In Figs. 10 and 11 the invention is shown in its application to a construction where the wall columns are not in alignment with 90 the interior columns. In such cases the structural member, which in the previously described embodiments, is encased in the column itself, is encased or anchored in the wall beam 68 extending from one wall column to another, and which forms the immediate support. In other respects the construction may be the same as that shown in Figs. 8 and 9, the head comprising I-beams 70 secured by bolts 72 to plates 74 to which 95 rods 76, forming the structural member anchored in the beam are secured by nuts 78 in a manner similar to that shown in said Figs. 8 and 9. In all of these constructions additional members, such as 80 may be used 100 to provide additional bearing or anchorage, as shown in Figs. 10 and 11, and any usual reinforcing structure, such as rods 82, see Fig. 8, may also be used, as will be readily understood by those skilled in the art. 110

It will also be manifest that my invention is applicable to flat slab systems using metal or clay tiles in combination with concrete, and also to drop panel constructions, in short to any flat slab construction. A drop panel is indicated at 84 in Figs. 6, 8 and 10.

It will be understood that my invention is applicable to structures in which the concrete column contains a structural column which is intended to carry the greater part of the load, the concrete column in such case serving more to encase the structural column and carry only a minor portion of the load. In the constructions shown in Figs. 1 to 3, and 6 and 7, for example, the H-irons 4 respectively could be extended downwardly to rest upon or be connected to the foundation, in which case they would constitute structural columns which would carry the greater 120 125 130

part of the load as above referred to. It will be apparent that the interior structural column in such cases need not have the form of an H-iron or I-iron, but may be of any 5 suitable form or construction.

A grout hole may be left in the top plate and in the bottom plate of the head. Such a grout hole is shown centrally of the plates at 48.

10 It will be apparent to those skilled in the art that my invention provides a reinforced construction by which the load is transferred directly from the floor to the concrete column or other support through the 15 head encased in the slab and the vertical structural member encased in the column, or directly to the interior structural column by means of the head, where an interior structural column intended to carry the load is 20 used. One of the main advantages of my construction lies in the fact that owing to its extreme strength, the use of capitals, usually employed at the junction of the tops of interior columns with the underside of the 25 slab or of wall column brackets, usually employed at the junction of wall columns with said slab becomes unnecessary. This represents a substantial gain in space and eliminates the unsightly capitals or brackets here- 30 tofore considered necessary, so that my invention is applicable to structures to be used for purposes for which the structures embodying the conical capitals or projecting wall brackets heretofore used are unsuitable.

35 My invention is peculiarly adapted to structures subjected to unbalanced strains, as the anchoring of the head to the vertical structural member and the extensive surfaces of said head and member furnish a 40 firm anchorage and offer adequate resistance to said strains.

It will be apparent that the use of my invention in no wise interferes with the usual reinforcing employed in the floors and 45 columns and that any such reinforcing structure may be employed in conjunction with my invention. In Fig. 3 the usual reinforcing structure for the column is shown in the form of rods 46.

50 It will be apparent that my invention will not interfere with the use of drainage or other pipes within the floors, the use of such pipes being perfectly feasible within the floors of structures embodying my invention.

55 Other advantages than those specifically pointed out will readily suggest themselves to those skilled in the art.

It is to be understood that the expression 60 "member" or "structural member" as applied to the vertical member within the column is to be interpreted in its broadest sense, and wherever used in this specification or claims may include a load bearing column within the concrete column as well

as a member extending only a certain distance above or below the floor or both above and below the latter. Similarly the term "head" is intended to include any structure suitable for the purpose described. 70

It will be apparent that it is not indispensable that all of the features of the invention be used conjointly, since they may be used to advantage separably in various combinations and sub-combinations. It will 75 also be understood that, while the invention is herein described as embodied in the details illustrated, it is not to be considered as circumscribed by or limited to these details, or any of them, but that said details may 80 be variously modified within the true scope of the invention which is definitely set forth by the claims.

Claims:

1. A reinforced concrete flat-slab construction, comprising reinforced concrete columns and a reinforced concrete floor slab and a metal structure embedded in said concrete, said metal structure comprising a vertical member embedded in the column 85 and comprising an H-iron and a head embedded in the slab and rigidly secured to said vertical member, said head comprising top and bottom plates rigidly secured to said vertical member and numerous radially disposed members of I-section whose inner 90 ends are located between and are rigidly secured to said plates.

2. A concrete construction comprising a 100 concrete slab and supports therefor, and a metal column frame embedded in the slab and the supports, said frame comprising upper and lower plates and numerous radially disposed members whose inner ends are located between and are secured to said plates and whose outer ends extend outwardly beyond said plates.

3. A concrete construction comprising 105 columns and a concrete slab supported thereby, a metal column frame embedded in the concrete, said frame comprising a head embedded in the slab and consisting of upper and lower plates and numerous radially disposed H-iron members whose inner 110 ends are located between and are secured to said plates, and a vertical structural member secured to said head and embedded in a column.

4. A concrete construction comprising 115 columns and a concrete slab supported thereby, a metal column frame embedded in the concrete, said frame comprising a head embedded in the slab and consisting of upper and lower plates and numerous radially disposed H-iron members whose inner 120 ends are located between and are secured to said plates, and a vertical structural member extending through and secured to said head and embedded in the column above and below said slab. 125

5. A metal column head frame comprising a head consisting of upper and lower plates and numerous radially disposed members whose inner ends are located between and are secured to said plates and whose outer ends extend outwardly beyond said plates.
6. A metal column head frame comprising a head adapted to be embedded in a concrete slab and consisting of upper and lower plates and numerous radially disposed H-iron members whose inner ends are located between and are secured to said plates, and a vertical structural member extending through and secured to said head and adapted to be embedded in the concrete column.
- 10

In testimony whereof I have signed my name to this specification.

ROBERT M. HARDISON.
